(57) **CLAIM**

The ornamental design for a multiple position air mattress system, as shown and described.

DESCRIPTION

FIG. 1 is a front elevational view of a multiple position air mattress system in accordance with the present invention, showing the new design in a first position as a chair;

FIG. 2 is a top view of the multiple position air mattress system of FIG. 1 in the first position;

FIG. 3 is a front view of the multiple position air mattress system of FIG. 1 in the first position;

FIG. 4 is a left side view of the multiple position air mattress system of FIG. 1 in the first position, the right side being a mirror image except for the valves;

FIG. 5 is a rear view of the multiple position air mattress system of FIG. 1 in the first position;

FIG. 6 is a bottom view of the multiple position air mattress system of FIG. 1 in the first position;

FIG. 7 is a front elevational view of the multiple position air mattress system of FIG. 1 in a second position as a recliner.

FIG. 8 is a front elevational view of the multiple position air mattress system of FIG. 1 in a third position as an inclined lounge; and,

FIG. 9 is a front elevational view of the multiple position air mattress system of FIG. 1 in a fourth position as a bed.

The broken lines in FIGS. 1-9 specifying exemplary top and bottom surface design of the mattress portions and the valves of the multiple position air mattress system form no part of the claim.
